UNITED STATES PATENT OFFICE.

EVERETT E. MOORE, OF FAUCETT, MISSOURI.

ROTARY VALVE.

1,146,644.

Specification of Letters Patent. Patented July 13, 1915.

Application filed August 13, 1913. Serial No. 785,225.

To all whom it may concern:

Be it known that I, EVERETT E. MOORE, a citizen of the United States, residing at Faucett, in the county of Buchanan and State of Missouri, have invented certain new and useful Improvements in Rotary Valves; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to rotary valves, and more particularly to a valve for controlling the intake and exhaust to and from the cylinders of explosive engines, the principal object of the invention being to provide positive mechanism for properly timing and controlling the volume of the intake and timing the exhaust.

In carrying out my invention I have provided improved details of structure, the preferred form of which comprises double or opposite ports so that the charges are admitted and exhausted simultaneously from opposite sides of the cylinder, in order to balance the cylinder and relieve same from strain due to the unequal heating of the walls, present in engines wherein the charge and burnt gases are either admitted and discharged from the same side of the cylinder, or from opposite sides, with the result that the temperatures vary at widely separated parts of the cylinders, and the cylinder expands and contracts unequally.

The embodiment of the invention also comprises other improved details of structure, the preferred forms of which are illustrated in the accompanying drawings, wherein:

Figure I is an end elevation of an explosive engine equipped with a rotary valve constructed according to my invention. Fig. II is a front view with part of the water jacket removed to illustrate the arrangement and partial construction of the valve and its mounting. Fig. III is a plan view of the parts shown in Figs. I and II. Fig. IV is a central longitudinal section of same. Fig. V is a transverse section on the line V—V, Fig. IV. Fig. VI is a detail section showing the connection between the inner and outer water-jackets or valve housings. Figs. VII and VIII are diagrams showing

the relative positions of the crank shaft and valve mechanism, throughout the four cycles.

Referring more in detail to the parts: 1 designates the engine cylinder which is mounted on a crank housing 2 and contains the usual piston 3 having a rod 4 connected with the crank shaft 5 of the engine.

The present cylinder has an intake port 7 and exhaust port 8 near its outer end, or preferably the paired ports, as shown, so that the intake and exhaust are paired to obviate strain and friction, the ports being arranged near the end of the cylinder and provided with interior channels 9 which are curved downwardly so that the charges are delivered into rather than across the cylinder, and so that the exhaust may flow freely to the outlet and thereby insure more perfect cleaning of the cylinder. The cylinder is provided with the usual spark plug 11 for insuring ignition after the charge has been admitted and compressed, although no invention is claimed on the use or construction of such a plug in the present device.

The cylinder 1 has an annular flange 13 on its outer face upon which a gear cup 14 is fixed by bolts 15, and mounted on said cup is a valve case 16 having inlet and exhaust conduits 17—18 registering with the inlet and exhaust ports 7—8 of the cylinder, the upper end of the case being turned inwardly at the top, and rigidly secured to the cylinder by bolts 19 which extend through the top of the case into bosses 20 at the upper edge of the cylinder, the valve case being spaced from the outer face of the cylinder to provide an annular channel 21 within which the valve may travel.

The valve proper comprises a cylindrical sleeve or collar 22 having paired ports 23 adapted for simultaneous registration with the paired intake ports of the cylinder and valve case, and for simultaneous communication with the exhaust ports, it being noted that the exhaust ports in the cylinder and case are larger than the inlet ports, so that the valve port remains in communication with the exhaust ports longer than with the inlet in order to give the engine sufficient time to clean. The valve fits snugly within the annular channel 21 but is adapted for free revoluble movement therein, the body of the valve being provided with teeth 24 on its lower edge which mesh with teeth 25 on the upper edge of the ring 26 of an annular gear wheel 27 that is located in the

cup 14 on the cylinder flange 13, so that the valve is supported and operatively connected with the gear wheel, although free to be lifted outwardly therefrom when the engine is to be taken apart.

The gear wheel 27 meshes with a pinion 28 of one-fourth its diameter, that is revolvably mounted in an extension case 29 on the gear cup 14, and rigidly fixed to a shaft 30 which extends through said case, and into a cap 31 therefor on the valve case 16, the shaft 30 being operatively connected through gearing and pinion mechanism 32 with a timing shaft 33 which is driven from the main crank shaft through spur gear wheels 34 and 35 of equal diameter.

In using the valve, presuming the parts to be constructed and assembled, as described, when the engine is not in operation, the valve is revolved within its channel so that its paired ports are brought into communication with the inlet ports or conduits, and in order that charges of vapor may be delivered into the interior of the cylinder, the gradual, although rapid, communication providing a gradual admission of the vapor to the cylinder and thereby assisting in providing a smooth and steady operation. As soon as the charge is admitted, continued revolution of the valve shuts off the intake, so that return of the piston compresses the charge within the cylinder to condition it for the explosion which takes place at the proper instant and is induced by a spark from the plug. Immediately after the explosion, the valve port comes into communication with the exhaust ports of the cylinder and casing so that the burned charge may be forced out of the cylinder by the cleaning stroke of the piston, the valve remaining in communication with the large exhaust ports a sufficient time to provide for proper exhaust of the burned gases, the spacing and timing of the various operations being indicated in the diagrammatic figures VII and VIII, in which it will be seen that there is a short interval between the closing of the exhaust valve and the opening of the inlet valve. I have found by experiment that the best results are obtained when this interval is five degrees, which would reduce to one and one-fourth degrees on the valve mechanism.

The mechanical equivalent of this arrangement is seen in Fig. V where the width

of the port 23 of the valve sleeve 22 is one and one-fourth degrees less than the width of that portion of the cylinder wall lying between the adjacent inlet and exhaust ports 7 and 8.

It is apparent from the foregoing description, and from the illustrations, that certain modifications may be made, such as making the ports square, providing other well known bearings for the gear ring and valve, connection between the valve and gear ring, etc., the present illustration being understood as a preferred form of construction.

Claims.

1. The combination with an engine cylinder, of a cup mounted on the cylinder, a valve case mounted on the cup to form an annular chamber and spaced from the cylinder to form an annular channel, a gear ring mounted in the cup and having teeth in its upper edge, a valve cylinder mounted in the channel and having teeth on its lower edge meshing with the teeth on the upper edge of the gear, and means for driving said gear, the cylinder case and valve being provided with suitable ports, for the purpose set forth.

2. The combination with an engine cylinder having a plurality of intake and exhaust ports and having an annular flange on its outer face, a cup mounted on said flange, a valve case mounted on said cup and having its outer end overlying the end of the cylinder, the body of the case being spaced laterally from the cylinder to form an annular channel, means for fixing the case to the cylinder, a gear ring revolvably mounted in said cup and having a toothed flange projected into said channel, a valve cylinder revolvably mounted in the channel and having a port adapted for registration with the intake and exhaust ports of the cylinder and case and operatively connected with the toothed flange of said gear ring, a pinion meshing with the gear ring, and means for driving said pinion from the crank shaft to the cylinder.

In testimony whereof I affix my signature in presence of two witnesses.

EVERETT E. MOORE.

Witnesses:
